CONTROL FOR AIR CONDITIONING SYSTEMS

Ritchie P. Dewey, Rockford, Ill., assignor, by
mesne assignments, to Barber-Colman Company,
Rockford, Ill., a corporation of Illinois

Application March 27, 1936, Serial No. 71,233

13 Claims. (Cl. 236—1)

This invention relates generally to air conditioning systems and more particularly to those of the so-called blast type in which the temperature of the air discharged into the space to be conditioned may be cooler or warmer than that in the space.

The primary object of the invention is to provide an air conditioning system of the above character having a plurality of temperature changing units and novel means for intercontrolling the operation of such units to prevent operation thereof at cross-purposes whereby to obtain optimum economy in operation and accuracy of temperature control.

15 A more detailed object is to provide a novel thermostatic control for governing the operation of a plurality of unit ventilating systems whereby the heater of either system will be maintained inactive so long as the fresh air damper 20 of the other system is opened beyond a predetermined minimum position.

Another object is to provide a novel system for thermostatically controlling the movements of the fresh air damper and the heat controller 25 in a heating system of the blast type.

Other objects and advantages of the invention will become apparent from the following detailed description taken in connection with the accompanying drawings, in which

30 Figure 1 is a plan sectional view of a room equipped with an air conditioning system embodying the novel features of the present invention.

Fig. 2 is a vertical sectional view of one of the 35 unit ventilators.

Fig. 3 is a schematic view and wiring diagram of the air conditioning units and the mechanism for controlling the operation thereof.

While the invention is susceptible of various 40 modifications and alternative constructions, I have shown in the drawings and will herein describe in detail the preferred embodiment, but it is to be understood that I do not thereby intend to limit the invention to the specific form 45 disclosed, but intend to cover all modifications and alternative constructions falling within the spirit and scope of the invention as expressed in the appended claims.

In the drawings, the invention is shown for 50 purposes of illustration embodied in a system for conditioning the air within a room 4 and comprising two so-called unit ventilators 5 and 5' arranged to discharge currents of conditioned air into different parts of the room and respectively controlled by thermostats 7 and 7' located with-

5 in the room at points remote from each other. The unit ventilator 5 comprises generally a casting 9 providing an air duct 10 communicating at one end with a fresh air inlet 11 and a duct 12 into which return or recirculated air from the room may enter through an opening 13 disposed adjacent the floor. A power driven blower 14 within the duct 10 operates to draw air through the inlets and discharge the same into the room through an opening 15.

10 The proportion of fresh air in the mixture is determined by the positions of dampers 16 and 17 located in the fresh and return air ducts and connected by a link 18 in a manner such that the fresh air damper is fully opened when the return 15 air damper is closed and the fresh air damper is completely closed when the return air damper is fully opened. By shifting the link back and forth, the proportion of fresh air in the mixture may be varied progressively. Thus, when 20 the temperature of the fresh air is below that of the room, the temperature of the recirculated air may be cooled to the desired degree by adjusting the position of the fresh air damper to correspond to the cooling requirements of the 25 room.

In the present instance, the fresh air inlet is 30 fully closed when the damper 16 or cooling regulator is in its minimum operating position. It will be understood, however, that a minimum operating position may be selected in which the fresh air inlet is partially open so that a predetermined minimum amount of fresh air will always be supplied to the room during operation 35 of the system.

Preferably the fresh and return air dampers 40 of the unit ventilator 5 are actuated by a power operator comprising an electric motor 19 connected through speed reduction gearing 20 to a shaft 21 which carries a crank 22 connected by a rod 23 to the link 18 so that the dampers 16 will be moved from the fully open position shown to fully closed position in a half revolution of the shaft 21 in a clockwise direction. The motor 45 shown is of the reversible shaded pole induction type having a main winding 24 constantly energized from an alternating current source 25 and having two sets 26 and 27 of shading coils arranged on the stator poles and adapted to be short-circuited selectively to cause the rotor 28 50 to turn in one direction or the other. The arrangement is such that the rotor will turn clockwise and the fresh air damper 16 will be closed progressively when the coils 27 are short-circuited. Reverse rotation and opening of the 55

fresh air damper occur when the coils 26 are short-circuited.

The unit ventilator 5 is equipped with a heating unit for supplying heat to the air delivered to the 5 room. Herein this unit comprises a heater in the form of a steam coil 29 herein interposed in the return air duct 12. The capacity of the heater may be varied progressively by modulating the opening of a valve 30 in the supply line 31 10 leading to the heater. This valve has a movable disk 32 which is actuated by an independent electric operator similar in construction to the damper operator, being moved toward and away from closed position by a cam 33 acting on a 15 follower 34 and fast on a shaft 35 operated by a reversing motor 36 having shading coils 37 and 38. When the coils 37 are short-circuited, the valve disk is moved toward open position, closing of the valve occurring while the coils 38 are active.

The thermostat 1 is of standard construction comprising a sensitive element 39 carrying a tongue having thereon the common contact of two switches 40 and 41 which are closed respectively when the room temperature is above and below the control point for which the thermostat is set. The thermostat 1' is similarly constructed.

The unit ventilator 5' is of the same construction as the unit 5, and the dampers and valve thereof are actuated by individual electric operators in the same way. The parts of the unit 5 are correspondingly numbered and identified by the exponent (').

In air conditioning systems of the above general character having independently operable heating and cooling devices controlled by the same or separate thermostatic means, conditions may prevail under which the devices tend to operate at cross-purposes. For example, due to drafts in the room, one unit may be operating on its cooling cycle while the thermostat controlling the other unit is calling for heat. To overcome this difficulty and provide for optimum economy in 45 operation and accuracy of control of the room temperature, the present invention contemplates a novel system of intercontrolling the individual operators of the same and of the different air conditioning units in a manner such that neither heater can be rendered active under the control 50 of its thermostat until the cooling device, that is, the fresh air damper 16 of the associated unit and also the cooling device of the other unit are in minimum operating positions.

In effecting such intercontrol, the electric motors 19 and 36 are placed in operative control of the thermostat 1 one at a time according to the positions of the valve and dampers. For this purpose, the short-circuit of the shading coils 27 60 extends from ground through the coils, a conductor 42, a limit switch 43 which is held closed by a cam 44 when the fresh air dampers 16 are in any other than fully closed position, a conductor 45, the switch 41 of the thermostat and to ground. The circuit for the coils 26 extends from ground 65 through the coils, a conductor 46, a limit switch 47 which is held closed by a cam 48 except when the dampers 16 are fully opened, a conductor 49, a switch 50 controlled by a cam 51, a conductor 70 52, a switch 53 controlled by a cam 54, a conductor 55, the thermostat switch 40 to ground. The cams 51 and 54 are similarly shaped and adapted to hold their switches closed only when the operating shafts 35 and 35' are in valve-closing positions. As a result of this circuit arrangement,

complete closure of the both valves 30 and 30' is a condition precedent to opening of the fresh air dampers 16 under the control of the thermostat switch 40.

When the fresh air dampers 16 are closed to their minimum operating position, the control of the thermostat 1 is transferred to the motor 36 so that the position of the valve 30 and therefore the capacity of the heater may be adjusted in accordance with the heating requirements in the room. To this end, the circuit for the shading coils 37 extends from ground through the coils, a conductor 57, a limit switch 58 which is closed by a cam 59 except when the valve 30 is fully open, a conductor 60, a switch 61 controlled by a cam 62, a conductor 63, a switch 64 controlled by a cam 65, and a conductor 66 joined to the conductor 45 which leads to the thermostatic switch 41. The cams 62 and 65 are so shaped that their switches will remain open when the fresh air dampers 16 and 16' are partially or fully open and will be closed only when the dampers are fully closed. As a result, the motor 36 cannot operate and accordingly the steam valve 30 cannot be opened under the control of the thermostat switch 41 until the fresh air dampers of both unit ventilators are closed. The circuit for the shading coils 38 extends from ground through the coils, a conductor 66, a switch 67 held closed by a cam 68 except when the valve 30 is fully closed, the conductor 55 and the switch 40.

The circuits for the motors 19' and 36' of the unit ventilator 5' are similarly controlled by the switches 40' and 41' of the thermostat 1'. Thus the coils 27' are short-circuited through a conductor 42', a limit switch 43', a conductor 45', and the switch 41'. The circuit for the coils 26' is through a conductor 46', the limit switch 47', a conductor 70, a switch 71 held closed by a cam 71' only when the valve 30 is closed, a conductor 72, a switch 73 held closed by a cam 74 when the valve 30' is closed and a conductor 75 leading to the switch 40'.

The coils 38' may be short-circuited through a conductor 66', and a limit switch 67' connected to the conductor 75 which leads to the switch 40'. The circuit for the coils 37' is through a conductor 57', a limit switch 58', a conductor 76, a switch 77 held closed by a cam 78 only when the dampers 16 are closed, a conductor 79, a switch 80 held closed by a cam 81 when the dampers 16' are closed, and a conductor 82 connected to the conductor 45' which leads to the switch 41'.

As a result of the circuit arrangement above described, it will be observed first that the heater 29 of either unit ventilator is maintained inoperative so long as the associated fresh air damper or the fresh air damper of the other unit ventilator is positioned to effect cooling of the room, that is, is partially open. Second, neither of the fresh air dampers can be opened under thermostatic control so long as either of the heaters is active as evidenced by partial opening of either steam valve. In this way, neither unit ventilator can operate on its heating cycle while the other is conditioned for cooling even though one of the thermostats may be calling for cooler air while the other is calling for heat.

I claim as my invention:

1. An air heating system having, in combination, a duct having an outlet communicating with a space to be heated, a fresh air inlet, a second inlet for receiving air to be recirculated from said space, a heater for the air in said duct, a damper controlling the fresh air inlet, a valve controlling

the flow of heating medium to said heater, a power operator arranged to impart graduated regulating movements of varying lengths in opposite directions to said damper, an independently operable power operator for modulating the opening of said valve, a thermostat responsive to temperature changes in said space, and means operating automatically in response to the movements of said damper and valve to place said thermostat in exclusive control of the damper operator when the valve is closed and the damper opened beyond a predetermined minimum position and to place the thermostat in exclusive control of said valve operator when said damper is closed to 15 said minimum position.

2. The combination with two unit ventilators arranged to deliver air to a room to be conditioned of a thermostat in the room acting to vary the proportion of return and fresh air delivered 20 by one of said unit ventilators, a thermostat located within the room at a point remote from said first mentioned thermostat and controlling the heater of the other unit ventilator, and means responsive to the movements of the fresh air damper of said first mentioned unit ventilator to maintain said heater ineffectual irrespective of the condition of said second thermostat so long as the fresh air damper of the first unit ventilator is opened beyond a predetermined position.

3. The combination with two unit ventilators arranged to deliver air to a room of independently operable thermostats located at spaced points within the room and each arranged to control the movements of the fresh air damper and the heat regulating device of one of said unit ventilators, and means operating automatically to maintain the heat regulating device of one unit ventilator inactive independently of its controlling thermostat so long as the fresh air damper of the other 40 unit ventilator is opened beyond a predetermined minimum position.

4. The combination with two unit ventilators arranged to deliver air to a room, of independently operable thermostats located at spaced points within the room and each arranged to control the movements of the fresh air damper and the heat regulating device of one of said unit ventilators, and means operating automatically to maintain the heat regulating device of either unit ventilator inactive independently of its controlling thermostat except when the fresh air dampers of both unit ventilators are closed to predetermined minimum operating positions.

5. The combination with two unit ventilators arranged to deliver air to a room, of independently operable thermostats located at spaced points within the room and each arranged to modulate the movements of the fresh air damper and the heater of one of said unit ventilators to vary progressively the temperature of the air delivered thereby, and means responsive to changes in the heat-delivering capacity of said heater and operating automatically to maintain the fresh air damper of one unit ventilator in a minimum operating position independently of the condition of its controlling thermostat so long as the heater of the other unit ventilator is supplying heat.

6. The combination with two unit ventilators arranged to deliver air to a room, of independently operable thermostats located at spaced points within the room and each arranged to control the movements of the fresh air damper and the heater of one of said unit ventilators, and means operating automatically to maintain the fresh

air damper of one unit ventilator in a minimum operating position independently of the condition of its controlling thermostat so long as the heater of either unit ventilator is active and supplying heat.

7. In a system for conditioning the air within a room, the combination of two unit ventilators each operable selectively to deliver cool or heated air to said room, two thermostats located at spaced points in said room and controlling said unit ventilators, and means intercontrolling the operation of the unit ventilators to prevent one from delivering heated air under the control of its thermostat while the other unit ventilator is delivering cool air.

8. The combination with two unit ventilators arranged to deliver air to a room, of independently operable thermostats located at spaced points within the room and each arranged to control the movements of the fresh air damper and the heat-regulating device of one of said unit ventilators, and means operating automatically to maintain the heat-regulating device of one unit ventilator in non-heating position independently of its controlling thermostat until the 25 fresh air damper of the other unit ventilator has been fully closed.

9. In a system for conditioning the space within a room of the building, the combination of means for delivering a mixture of fresh and recirculated air to said room, a damper controlling the proportion of said fresh air in said mixture, thermostatically controlled means modulating the movements of said damper, a heater for supplying heat to the room, an independently operable thermostat within the room, a power operator controlled by said thermostat and operating to modulate the heating capacity of said heater, and means responsive to the movements of said damper and automatically controlling said operator to maintain the heater inactive independently of said thermostat while said damper is open to a predetermined position and to restore the control of the thermostat when the damper is closed to such position.

10. In a system for conditioning the space within a room of the building, the combination of means for delivering a mixture of fresh and recirculated air to said room, a damper controlling the proportion of said fresh air in said mixture, thermostatically controlled means modulating the movements of said damper, a heater for supplying heat to the air, an independently operable thermostat controlling the operation of said heater, and means operating automatically to withdraw the heater from the control of said thermostat when the damper is open to a predetermined position and to restore the control of the thermostat when the damper is closed to such position.

11. In a system for conditioning the air within a building, the combination with a device movable back and forth to control the cooling of the air in the space to be conditioned, a power operator for modulating the movements of said device to vary the cooling progressively, a thermostat controlling said operator, a heater for delivering heat to said space, a regulating member for varying the capacity of said heater, a power operator for modulating the movements of said member, a thermostat controlling said last mentioned operator in response to temperature changes of the conditioned air, and means operating independently of said second thermostat and controlling said second operator to maintain said member in non-heating position until 75

the cooling effect controlled by said first mentioned device has been reduced to a predetermined minimum.

12. The combination of a duct through which a current of air is passed into a room the temperature of which is to be controlled, a device having a predetermined minimum operating position and movable out of such position to control the cooling of said air current, a second device having a predetermined minimum position and movable out of such position to control the heating of the air current, independently operable power operators for imparting modulating movements to said devices, thermostatic means controlling said operators to determine the direction and extent of movement of said devices, and means operating independently of said thermostatic means and by movements of said devices to intercontrol said operators and prevent movement of one device away from its predetermined position until the other device has been returned to its predetermined position.

13. In a system for tempering the air within a building, the combination with a device movable back and forth to modulate cooling of the space to be conditioned in accordance with its position relative to a predetermined position, a heat control device movable back and forth to modulate heating of the space in accordance with the position of the device relative to a predetermined position, individual thermostatic actuators for the respective devices each operable in response to temperature changes in said space to control the direction and extent of modulating movement of its associated device, and automatically operating means responsive to movements of one of said devices for intercontrolling the operation of said actuators to maintain the other device in its predetermined position until the former device has been returned to its predetermined position. 5 10 15
